Patented Feb. 17, 1920.

UNITED STATES PATENT OFFICE.

WAYLAND D. MICHENER, OF ROSELLE PARK, NEW JERSEY, ASSIGNOR TO THE SINGER
MANUFACTURING COMPANY, A CORPORATION OF NEW JERSEY.

SEWING-MACHINE.

1,331,164.

Specification of Letters Patent. Patented Feb. 17, 1920.

Application filed November 13, 1916. Serial No. 130,997.

To all whom it may concern:

Be it known that I, WAYLAND D. MICHENER, a citizen of the United States, residing at Roselle Park, in the county of Union and

5 State of New Jersey, have invented certain new and useful Improvements in Sewing-Machines, of which the following is a specification, reference being had therein to the accompanying drawings.

10 The present improvement relates to sewing machines having a reciprocating needle, a work-holder, and means for producing relative lateral jogging movements between said needle and work-holder in the formation of 15 detached groups of fastening stitches, and has for an object to provide a machine of this type with work holding mechanism adapted to compress and hold a bundle of yarn-strands or the like during the stitching 20 operation thus adapting the machine to the manufacture of tufted balls or tassels by the well known method of first sewing a bundle of yarn-strands together at intervals and subsequently cutting the body of yarn between the groups of stitches. This method 25 is disclosed, for example, in the U. S. patent to Doolittle, No. 254,935, dated March 14, 1882.

It is undesirable, however, to rotate the 30 compressed bundle of yarn-strands during the stitching operation as is done in the above mentioned Doolittle patent, particularly when the yarn-strands are to be simultaneously sewed together and to a suspension 35 cord supported by a strip of braid or fringe, and the invention has for a further object to provide a special form of work-clamp adapted to hold the yarn-strands in a compressed condition, and to provide mechanism for 40 producing relative bodily movements between the needle and work-clamp, whereby the yarn-strands may be sewed together without rotating the latter.

A further object of the invention is to provide means for stopping the machine with the parts in such a position that the needle will not interfere with the ready removal of the finished work.

Further objects of the invention will appear in the following description and claims.

The invention is shown embodied in a machine of the well known flat-bed button sewer type such as disclosed in the patent to Sullivan, No. 777,564. In the present instance the work-holder consists of a work

supporting plate on which are mounted two up-standing work confining guides which are spaced apart and define a work receiving throat between them. The work plate is provided with an elongated needle aperture 60 extending across and somewhat beyond the space between the work confining guides and the latter are grooved vertically to receive the needle as it descends alternately at opposite ends of the needle aperture. A presser-foot, having a pair of arched toe-portions and a weighted heel is pivoted to the upper work-clamp arm and adapted to condense the yarn-strands placed in the work receiving throat.

In order that the stitched work may be readily removed from the clamp without striking the needle, the work-holder actuating cam is, in the present instance, so constructed as to place the work engaging members in a forward position during the production of the usual tying stitches, so that when the machine is stopped the space above and in front of the work receiving throat is not unduly impeded by the needle.

To gain a better understanding of the invention reference may be made to the accompanying drawings in which Figure 1 is a perspective view of a machine embodying the invention. Fig. 2 is a plan view of the work engaging portions of the work-clamp, and Fig. 3 is a side elevation of the parts shown in Fig. 2.

In the present instance the invention is shown embodied in a machine constructed 90 substantially in accordance with the disclosure of said Sullivan patent and having the usual flat bed 1, standard 2, and arm 3 in which is journaled the main-shaft 4 connected through the pitman 5 to the needle-bar 6 carrying the eye pointed needle 7. Journaled in rear of the needle-bar 6 is a spring pressed presser-bar 8 adapted to be lifted by means of the lever 9 and the usual treadle connection. Geared to the main-shaft 4 is the cross-shaft 10 on which is mounted the pattern-cam 12 formed with a cam-slot 13 and carrying the usual tripping point 14 which in practice actuates a latch-lever 15 to release the starting and stopping 100 lever 16 of the well known stop-mechanism common to machines of this type. The machine is preferably provided with the well known device disclosed by said Sullivan patent for cutting the stitching thread beneath 110

the work at the completion of each group of stitches. This device has not been illustrated, however, since it forms no part of the present invention.

- 5 The work-holder comprises the usual slide-bar 20 which carries a block 21 adjacent its rearward end in which is journaled for slight vertical movement an upper work-clamp arm 22 extending above and substantially parallel with the slide-bar 20 and pressed normally downward by means of the usual arched pressure spring 23 secured upon the block by a screw-bolt. Secured to the forward end of the slide-bar 20 is a 10 work-supporting plate 24 having a needle-aperture 25 which is elongated in the direction of the length of the slide-bar 20. Rising from the work-supporting plate 24, at opposite ends of the needle-aperture, are two 15 up-standing work-confining guides 26, 27 which are spaced apart and define a work-receiving throat α between them. The upper end-portions of the work-confining guides are oppositely curved, away from each other, 20 and form an upwardly flaring mouth; the upper end-portion of the forwardly disposed guide being extended forwardly to form a flattened horizontal lip 28 which acts as an auxiliary guide to facilitate insertion 25 of the strands into the mouth of the work-holder. The distance between the opposed work-engaging surfaces 29, 30 of the guides is less than the length of the elongated aperture 25 in the work-supporting plate 30 and the portion of each guide which stands directly over an extremity of the needle-aperture is cut away at 31 to receive the needle, so that it may descend alternately 35 at opposite sides of the confined yarn-strands without passing through the latter. 40 Secured to the forward extremity of the upper clamp-arm is the horizontally extended shank 32 of the bifurcated presser-foot p which co-operates with the work-confining guides to compress and hold the yarn-strands in stitching position. The presser-foot p is secured between its ends to the 45 downwardly and forwardly extended free end of the shank 32 by a pivot pin 32' and is formed with a weighted heel 33 and two spaced and arched toe-portions 34, 34 which are extended forwardly at opposite sides of the elongated needle-aperture 25 and work-confining guides 26, 27 so that they may 50 bear upon the yarn strands and condense them into a compact bundle preparatory to the stitching operation. The upper clamp-arm 22 may be lifted through the usual connections with the presser-bar, 8 and when 55 so lifted the weighted heel 33 of the presser-foot will drop and elevate the toes 34 to the position shown in dotted lines in Fig. 3, in which position the toes 34 are so related to the guides 26, 27 and 28 that said toes 60 65 act as auxiliary guides, in deflecting the

work downwardly into the throat α , and prevent accidental movement of strands over the top of the rearwardly disposed guide 27 during the work-inserting operation. By arranging the work-confining 70 guides 26 and 27 so that they embrace the needle-aperture, and by providing the spaced presser elements 34 for compressing the yarn in the throat α at spaced points on opposite sides of the stitching point, the yarn strands 75 will be securely held in the form of a compressed bundle and may be readily bound tightly together by the fastening means.

Longitudinal movements are imparted to the work-holder through the usual connections with the pattern-cam 12 which comprise a vertical post 35 mounted at the rearward extremity of the slide-bar 20 and carrying an adjustable block 36 fitted within the slotted arm 37 of the two-armed rock-lever whose other arm 38 carries a cam-roller 39 fitted within the cam-slot 13. In the present machine this cam-slot is of special form and is designed to so jog the work-holder as to cause the needle to form the first 80 stitch near the rearward extremity of the needle-aperture in the work-supporting plate, yet within the bundle of yarn-strands. The second stitch is made in the yarn at a point forward of the first stitch; the third 85 stitch at the forward extremity of the needle-aperture; the fourth stitch within the yarn and the fifth stitch at the rearward extremity of the needle-aperture. Subsequent 90 stitches are formed alternately at opposite 95 sides of the yarn but not within the latter and bind the strands tightly together; the last three stitches of the group being made at the same point where the first stitch was made. These last stitches serve to knot the 100 stitching threads in the manner described in the said Sullivan patent. The usual mechanism for jogging the work-holder laterally of itself in machines of this type 105 is not utilized in the present instance and is dispensed with. A guide-block 40, secured to the bed-plates of the machine, is provided with a slideway 41 which receives the slide-bar 20 and confines the said bar against lateral movement.

In the operation of the machine the presser-foot p is lifted to the dotted line position, Fig. 3, and a bunch of yarn-strands s are advanced over the lip 28 and into the throat α . At this time the elevated toe-portions 34 act as auxiliary guides and form together with the lip 28 an enlarged and forwardly opening mouth leading to said throat. If it is desired that the tufts be attached to suspension cords, a loop of such 110 cord e is also placed in said throat. The presser-foot is next lowered whereupon the arched toe-portions 34 descend and act to round over and compress the yarn-strands 115 into a compact bundle adjacent the stitch- 120 125 130

- ing point, as shown in Fig. 1. The machine is then started whereupon the work-holder is jogged laterally of the needle path and a group of stitches are formed about the yarn-strands to bind them tightly together. After the stitching operation the work may be removed and the yarn severed to permit expansion of the cut ends into the form of a tufted ball or tassel such as shown at *t*.
- 10 The form and arrangement of the parts constituting the invention are clearly susceptible of material modification within the scope of the appended claims and it is to be understood that the invention is not limited to the use of any particular type of 15 stitch forming mechanism and that it is immaterial, in the broad aspect of the invention, whether the relative jogging or stitch positioning movements are secured by 20 jogging the needle or the work-holder or both the needle and work-holder.
- Having thus set forth the nature of the invention, what I claim herein is:—
1. In a sewing machine, in combination, 25 stitch-forming mechanism including a reciprocating needle, a work-support formed with a yarn-receiving throat, a presser-member adapted to compress a bunch of 30 yarn-strands in said throat and hold said 35 yarn strands fixed relative to said throat during a succession of stitch-forming cycles, and means for producing relative to-and-fro 40 stitch-positioning movements between said needle and work-support to cause a localized group of binding 45 stitches to be formed about said bunch of yarn-strands.
2. In a sewing machine, in combination, 50 stitch-forming mechanism including a reciprocating needle, a stop-motion for controlling its period of action, means including work-supporting and vertically movable 55 presser members shaped to compress and wholly inclose a bunch of yarn strands adjacent the stitching point, said members 60 operating to hold the yarn strands fixed relatively thereto during the stitching period, and means for producing relative jogging 65 movements between said needle and yarn-holding means in directions transversely of the path of reciprocation of said needle.
3. In a sewing machine, in combination, 70 stitch-forming mechanism including a reciprocating needle, a yarn-holder including relatively movable work-supporting and 75 presser-members, said work-supporting member having opposed upstanding yarn-confining surfaces between and relative to which the yarn is held fixed by the presser-member during the stitching operation, and means 80 for producing a plurality of relative jogging movements between said needle and yarn-holder in directions transversely of the space between said surfaces while the yarn is held in fixed relation to the yarn-holder.
4. In a sewing machine, in combination, 85 stitch-forming mechanism including a reciprocating needle, a yarn-holder including relatively movable work-supporting and presser-members, said work-supporting member having spaced upstanding yarn-confining surfaces, and means for producing relative lateral jogging movements between said needle and yarn-holder in directions transversely of the space between said surfaces, 90 said movements being of greater amplitude than the distance between said surfaces adjacent the stitching point, whereby a bunch of yarn strands is wholly inclosed by the group of stitches formed.
5. In a sewing machine, in combination, 95 stitch-forming mechanism including a reciprocating needle operating to form a predetermined number of stitches, a work-holder comprising a pair of spaced yarn-confining guides disposed, respectively, in front and in rear of the needle-path and a presser-device including spaced work-engaging portions disposed at the sides of the needle-path and adapted to compress a bunch of yarn-strands placed between said 100 guides and grip the yarn-strands throughout the formation of said stitches, and means for producing relative stitch-positioning movements between said stitch-forming mechanism and work-holder across the space between said guides, whereby said stitches are grouped together at one point along the length of said yarn-strands.
6. In a sewing machine, in combination, 105 stitch-forming mechanism including a vertically reciprocating needle, a support having guide surfaces defining an upwardly opening yarn receiving throat between them, a presser-member mounted on said support for compressing and holding a bunch of 110 yarn-strands in said throat, and means for jogging said support laterally of said needle.
7. A special work-holder for sewing machines comprising, a support having opposed guide surfaces defining a yarn-receiving throat between them, and a presser-member movable vertically to a depressed position beyond the mouth of said throat for compressing and holding a bunch of 115 yarn-strands in said throat, and means for jogging said work-holder widthwise of said throat.
8. A special work-holder for sewing machines comprising relatively movable opposed clamping members, one of said members having opposed yarn-confining surfaces defining an upwardly opening yarn-receiving throat, and the other of said members being movable to a depressed position below the mouth of said throat to compress 120 the yarn confined therein, and means for jogging said work-holder to-and-fro in the direction of the shortest distance between said surfaces.
9. A special work-holder for sewing ma- 125

- chines comprising, a support having a needle-aperture embraced by guide-surfaces defining an upwardly opening work-receiving throat, and spaced presser elements embracing said throat and movable below the mouth thereof for compressing and holding the work therein.
10. A special work-holder for sewing machines comprising, a support formed with a yarn-receiving throat, a presser-member carried by said support and adapted to press a bunch of yarn-strands into and entirely beyond the mouth of said throat, and means for jogging said work-holder.
- 15 11. A special work-holder for sewing machines comprising, a support having an elongated needle-aperture and opposed work-confining surfaces at opposite sides of said aperture, said surfaces being disposed inwardly from the ends of said aperture and defining an upwardly opening throat, and a presser-member for compressing and holding a bunch of yarn-strands between said surfaces.
- 20 12. A special work-holder for sewing machines comprising, a support having an elongated needle-aperture and opposed up-standing work-confining surfaces located at opposite sides of said aperture and defining an upwardly opening throat, the distance between said surfaces being less than the length of said aperture, and a presser-member for compressing and holding a bunch of yarn-strands between said surfaces.
- 25 13. A special work-holder for sewing machines comprising a support having guide surfaces defining an upwardly opening work-receiving throat, a pivotally mounted presser-foot having toe portions adapted to compress and hold the work in said throat, a presser-foot lifter, and means whereby said toe portions are swung upwardly about their pivot when said presser-foot is lifted.
14. A special work-holder for sewing machines comprising a support having guide surfaces defining an upwardly opening work-receiving throat, a pivotally mounted presser-foot for compressing and holding the work in said throat, said presser-foot including toe portions and a weighted heel, and means for lifting said presser-foot.
15. A special yarn-holder and compressor for sewing machines comprising a work-supporting plate, a pair of spaced upstanding guides mounted on said plate and having opposed yarn-confining surfaces defining an upwardly opening throat, and a presser-member opposed to said plate and adapted to compress the yarn positioned between said guides, said guides having grooves to receive the needle and said plate having an elongated needle-aperture the extremities of which register with said grooves.
- 60 16. A special work-clamp for sewing ma-

chines comprising, in combination, a lower supporting plate having a needle-aperture, a pair of spaced up-standing work-confining guides carried by said plate and embracing said needle-aperture, and an upper clamp-member including a presser-foot having a pair of toe-portions extending along opposite sides of said guides and adapted for movement below the upper extremities of said guides to confine the work in the space therebetween.

17. A special work-holder for sewing machines comprising, a support and a pair of spaced, up-standing, work-confining guides carried by said support, the upper end of one of said guides being extended outwardly to form an auxiliary guide facilitating insertion of the work into the space between said guides.

18. A special work-holder for sewing machines comprising, a support, a pair of spaced up-standing guides carried by said support and defining a work-receiving throat, the upper end of one of said guides being extended outwardly away from the other guide, a presser-foot including spaced work-engaging toes extended forwardly at opposite sides of said guides, and means for lifting said presser-foot, said toe-portions serving, when lifted, as auxiliary guides facilitating insertion of the work into said throat.

19. In a sewing machine, in combination, a reciprocating needle, a work-holder comprising forwardly and rearwardly disposed guides defining an upwardly opening throat between them, means for producing relative forward and rearward jogging movements between said needle and guides, and means for stopping the machine with the needle nearer the rearward guide whereby the work may be readily removed without striking the needle.

20. In a sewing machine, in combination, a reciprocating needle, a work-holder comprising forwardly and rearwardly disposed guides defining an upwardly opening work-receiving throat between them, means for producing relative forward and rearward jogging movements between said needle and guides, said means being actuated to cause the needle to make the first stitch within the body of the work, subsequent stitches alternately beyond opposite sides of the work, and the last stitch within the body of the work but nearer the rearwardly disposed guide.

21. A special work-clamp for sewing machines, comprising a work-support formed with opposed guides defining an open sided throat and a bifurcated presser-foot having work-engaging portions movable depthwise of and along the open sides of said throat, said work-support having a needle-clearance aperture at the bottom of said throat.

22. A special work-clamp for sewing machines, comprising a supporting member having a needle-aperture, upstanding guides carried thereby and disposed in spaced relation embracing said aperture to define an open sided throat and a presser-foot mounted on said supporting member and having spaced work-engaging portions movable depthwise of and along the open sides of said throat.
23. In a sewing machine, in combination, stitch-forming mechanism including a reciprocating needle, a work-support formed with opposed upstanding guides defining a throat having oppositely disposed open sides, spaced presser elements movable depthwise of and along the open sides of said throat at opposite sides of the needle-path and means for producing relative
- stitch-positioning movements between said needle and work-support to lay the stitches about a bundle of yarn-strands confined in said throat.
24. In a sewing machine, in combination, stitch-forming mechanism including a vertically reciprocating needle, a work-support having an elongated needle aperture, guides carried by the work-support and presenting opposed upstanding yarn-confining surfaces at opposite sides of said needle aperture, a presser for compressing and holding a bunch of yarn-strands placed between said guides, and means for relatively jogging said needle and work-support in directions lengthwise of said aperture.
- In testimony whereof I have signed my name to this specification.
- WAYLAND D. MICHENEN.
